(57) **CLAIM**

The ornamental design for a desk, is shown and described.

DESCRIPTION

FIG. 1 is a front perspective view of the desk showing the design;

FIG. 2 is a front elevation view thereof;

FIG. 3 is a sectional view taken along the section line 3—3 of FIG. 2;

FIG. 4 is a sectional view taken along the section line 4—4 of FIG. 2;

FIG. 5 is a rear elevation view thereof;

FIG. 6 is a top plan view thereof;

FIG. 7 is a bottom plan view thereof;

FIG. 8 is a right elevation view thereof, the left elevation view being a mirror image in a standard configuration;

FIG. 9 is a top plan view showing the desk in a modified arrangement, in which the side table is in an alternate position to that shown in FIGS. 1 to 8; and,

FIG. 10 is a top elevation view showing the desk in a modified arrangement, in which the side table is in an alternate position to that shown in FIGS. 1 to 8.

The broken lines are for environmental purposes only and form no part of the claimed design.
